CLAIM

The ornamental design for an anti-snag jumper cable, as shown and described.

DESCRIPTION

FIG. 1 is a perspective view of an anti-snag jumper cable showing my new design;

FIG. 2 is a top view of an anti-snag jumper cable showing a pair of clamping members on an enlarged scale. The remainder of the cable is omitted for convenience of illustration;

FIG. 3 is a side view thereof;

FIG. 4 is a rear view of an anti-snag jumper cable showing a single clamping member on a further enlarged scale. The remainder of the cable is omitted for convenience of illustration; and,

FIG. 5 is a front view of an anti-snag jumper cable showing a pair of clamping members on the same scale as FIG. 4. The remainder of the cable is omitted for convenience of illustration.
